SELECTOR DEVICE

William A. Patzer, Chicago, Ill., assignor to
L. W. Menzimer, trustee, Rockford, Ill.

Application June 25, 1956, Serial No. 593,426

14 Claims. (Cl. 74—483)

This invention relates to a machine for vending various articles of merchandise, such as candy, cigarettes, beverages, canned goods, milk and the like, wherein various brands or articles are available for selection. It relates more particularly to a device for use in a machine of the type described which enables selection to be made by the vendee independently of any previous operation of the machine or any previous selection but without permitting operation of the machine for delivery of more than the one article selected.

This application is a continuation-in-part of application Ser. No. 574,200, filed March 27, 1956, and entitled "Selector Device."

It is an object of this invention to provide a device of the type described which may be used as a selector operable by the vendee for the selection of articles desired to be delivered by the vending machine.

Another object is to provide a device of the type described which enables selection to be made without limitation by reason of any previous selection prior to the operation of the machine through its vending cycle and independently and without influence by the arrangement of parts from any previous operation of the machine thereby to permit complete freedom and flexibility in the selection of articles to be delivered from the machine.

A further object of this invention is to provide a device of the type described which prevents simultaneous operation to vend other than the one selected article from the machine and which permits operation for subsequent selection for delivery without the necessity to return all of the elements to a normal position of adjustment thereby to make the machine completely independent of its previous operations.

A still further object is to provide a selector device of the type described which is formed of relatively few simple parts that are easily assembled into a unit capable of prefabrication, which requires very little, if any, maintenance or repair, and which makes use of elements that remain free to move in all positions of adjustment thereby to permit operation independently of position.

These and other objects and advantages of this invention will hereinafter appear and for purposes of illustration, but not of limitation, embodiments of the invention are shown in the accompanying drawing, in which—

Figure 1 is a fragmentary top plan view of a portion of the selector device embodying the features of this invention;

Figure 2 is a view similar to that of Figure 1 showing the arrangement of parts when one of the plungers is displaced for selection;

Figure 3 is similar to that of Figures 1 and 2 showing the arrangement of parts when another one of the plungers is displaced for selection;

Figure 4 is a sectional view taken along the line 4—4 of Figure 3;

Figure 5 is a sectional view taken along the line 5—5 of Figure 4;

Figure 6 is a sectional view taken along the line 6—6 of Figure 4;

Figure 7 is a sectional view taken along the line 7—7 of Figure 4;

5 Figure 8 is a perspective view of a portion of the device shown in Figure 1 but illustrating a modification in the construction of the plunger; and

Figure 9 is a perspective view of one of the disc members employed in the device described.

10 To the present, various means have been employed for selection of an article to be vended from a machine. In the main, these have constituted rather large and cumbersome units constructed of a plurality of levers or other elements interconnected for rocking movement

15 about separate pivots with the ends of the levers in operative engagement one with the other for rocking movement or displacement of all of the elements to one side of the lever associated with the selector rod operated thereby to effect operation of the machine through a cycle. Before operation of a subsequent cycle, the elements described are generally returned to their normal position for setting the machine to enable a subsequent selection to be made which would otherwise be prevented.

Further, in a device of the type heretofore employed, 20 the operation of all of the elements interconnected or in contacting relation one with the other complicates the machine and the construction thereof to the extent that interferences arise in operation and shut-downs for repair or replacement of parts occur quite frequently.

25 The inflexibilities experienced in the operation of selector devices heretofore employed and the large space required for the assembly of the selector device in a vending machine have been obviated, in accordance with the practice of this invention, by the use of a device of considerably smaller dimension and simpler construction wherein freedom of operation is secured and wherein greater flexibility in operation is made available.

30 As illustrated schematically in the drawing, independently of the vending machine adapted to be operated thereby, the selector device embodying the features of this invention comprises a plurality of disc members, such as the three disc members 10, 12 and 14 illustrated in the drawing, formed of rigid material, such as plastics, metals and the like, and preferably formed of a material which is resistant to corrosion and which is somewhat self-lubricating in character so as to be free for operation as a bearing or slide, as will hereinafter be defined.

35 The disc members, preferably of uniform dimension, are arranged in side by side relation within a guide slot 16 formed within a plate 18, as in the top wall of an H casting, such as illustrated in the drawing. The guide slot 16 is dimensioned to have a width corresponding to the diameter of the disc members and a depth corresponding to the thickness of the disc members to permit the disc members to be received therein for free sliding or rolling movement laterally without too much play in the endwise direction and without enabling the disc members to 40 straddle one another when the slot is enclosed by a cover plate 20 which preferably extends continuously over the slot and is fixed or otherwise secured to the top side of the plate.

45 The disc members 10, 12 and 14 are arranged within the slot between stops in the form of studs 22 and 24 extending upwardly through an intermediate portion of the slot and spaced laterally one from the other by a distance corresponding to the combined diameters of the disc members plus the thickness of a plunger 26 or slide adapted to be projected therebetween in operation.

50 Instead of studs or pins 22 and 24, use may be made of other abutments or stops having the described spaced re-

lation therebetween. For example, use may be made of walls which define the ends of the slots or the like or use may be made of projections extending inwardly from the side walls of the H casting into position to be engaged by the lateral edge portions of the outermost disc members for limiting the extent of sidewise movement. It is preferred to make use of pins or studs which can be secured in position of use within the slot so as to enable the casting or plate to be formed in endless strips for cutting to lengths corresponding to the number of slide and disc members to be used therewith.

The plungers 26 or slides comprise elongate metal members preferably formed to be rectangular in cross section and mounted for endwise sliding movement in slots 28 and 30 extending lengthwise through the upper portions of the front and back walls 32 and 34 respectively forming a part of the plate or H casting to provide guides for the plungers in endwise movement. Each of the pairs of slots 28 and 30 for receiving a plunger or slide is spaced crosswise in the casting by an amount corresponding to the diameters of the disc members located within the guide slot 16 so as to align the plungers with the lateral edge portions of the disc members for camming action in operation to effect displacement as will hereinafter be described. As a result, the number of plungers or slides 26 employed can correspond to one more than the number of disc members 10, 12 or 14, as illustrated by the four slides 26, 26^a, 26^b and 26^c in the drawing, with the outermost slides 26 and 26^c aligned with the lateral edge portions of the outermost disc members 10 and 14, while the intermediate plungers are aligned with the lateral edge portions of the middle disc member 12 and the disc members adjacent thereto. Any number of plungers less than one more than the number of disc members may be used with the plungers aligned with one or the other of the lateral edge portions of the disc members for effecting the desired displacement by camming action, in position of use.

Each plunger is dimensioned to have a length substantially greater than the width of the plate or casting with a forward end portion 36 extending through the opening beyond the front wall 32 of the casting for a substantial distance, when in normal position, and a lesser distance when in operated position. The portion extending forwardly beyond the front wall may be provided with a knob or other means for enhancing a gripping relation to be established for manual operation of the plunger between normal and operated positions of adjustment.

The plunger is dimensioned to provide a rearward end portion 38 which extends through the slot 30 in the rear wall of the casting to extend a greater or lesser distance from the rear wall in the operated and normal positions of adjustment respectively. In the illustrated modification, the plunger is cut away in the rearward upper edge portion to provide an upwardly inclined section 40 which operates as a cam to effect displacement of a switch arm 42 to make or break a switch 44 responsive to movement of the plunger between normal and operated positions. For this purpose, switch members 44 are mounted on the top wall 20 with a switch arm extending downwardly through a rearward opening 46 in alignment with the plunger for enabling the switch arm 42 to extend downwardly through the opening into resilient engagement with the upper edge of the plunger. Thus when the plunger is in normal position, as illustrated in Figure 5, the roller 48 on the end of the switch arm extending downwardly through the opening 46 rests upon the upper edge portion of the plunger rearwardly of the cam whereby the switch arm is in its lowered or un-made position. During movement of the plunger from normal to operated position, as illustrated in Figure 7 of the drawing, the rearward displacement of the plunger brings the cam surface into operative engagement with the roller 48 on the end of the switch arm 44 to cause the latter to be rocked upwardly about its pivot and to make the switch 44

65

70

which is aligned to be operated by the switch arm. When the plunger is returned to normal position, the roller rides down the cam to rock the switch arm in the clockwise direction about its pivot to break the switch. It will be understood that other means responsive to displacement of the plunger during movement from normal to operated positions and from operated to normal positions may be employed to make and break the switch respectively.

The intermediate portion of the plunger, usually located within the guide slot 16, is formed with a recess 50 in the upper edge portion. This recess is formed to have a depth to bring the bottom of the recess substantially flush with the surface of the slotted plate so as to provide a relatively continuous surface crosswise over which the disc members can slide. The length of the recess 50 is preferably dimensioned to be less than the width of the slot 16 but greater than the cord through the disc members spaced a distance from the edges thereof by an amount corresponding to the width of the plunger so that this portion of the disc members may be displaced into the recess during operation. However, the recess may be of a greater length as long as the forward edge is free of the disc members in normal position and alongside the disc members when the plunger is displaced to operated position. When in normal position, the recess 50 is dimensioned to be centered lengthwise within the guide slot and the amount of displacement of the plunger from normal to operated position is adapted to bring the plunger defining the forward edge portion of the slot into camming engagement with the curvilinear lateral edge portions of the disc members for displacement therebetween. Thus the stroke of the plungers between normal and operated positions is intended to correspond to an amount sufficient to bring a portion of the plunger at the level of the disc plates to at least the center of the guide slot thereby to space the adjacent disc members by an amount corresponding to the thickness of the plunger.

Various means may be employed for stopping the plunger and to determine its normal and operated positions of adjustment. One such means can include a stop in the form of pins 52 extending laterally from the forward end portion of the slide for abutment against the front wall of the casting when the plunger is displaced to operated position as illustrated by the position of plunger 26^c in Figure 3. A similar stop or pin 54 extending laterally in the rearward end portion of the plunger can be employed for abutment against the rear wall of the casting when the plunger is displaced from operated to normal positions of adjustment as illustrated in Figures 1, 2 and 3. Instead of making use of a pin located in the plunger to extend laterally in position to engage the front wall of the casting, the knob (not shown) mounted on the forward end portion of the plunger may be adapted to abut against the front wall of the casting when the plunger is displaced to its operated position of adjustment.

In the preferred concept of this invention, as illustrated in Figure 8 of the drawing, the plunger or slide 26 is dimensioned to have a portion extending rearwardly from the H casting to space the rearward end thereof from a wall 56 by an amount corresponding to the stroke of the plunger between normal and operated positions whereby the end of the plunger is stopped upon engagement with the wall 56. The rearward end portion of the plunger is formed with a downwardly extending offset 58 which provides a stop shoulder 60 in position to engage the rearward wall of the casting when the plunger is returned from operated position to normal position. It will be understood that various other means within the art may be adapted for use as stops to control movement of the plunger between normal and operated positions of adjustment.

Means are employed constantly to urge the plungers independently in the direction toward their normal position automatically to return the slide from operated to

75

normal position upon release. Various means can be employed for such purpose such as the tension spring 70 having one end 72 secured to a hook 74 depending from the rearward end portion of the plunger, as illustrated in Figures 5 and 7 of the drawing. The other end of the spring 70 can be anchored onto the rear wall 34 of the casting or onto the front wall 30, as illustrated in the drawing. Instead of a tension spring of the type described, use can be made of other means such as a compression spring 76 located between the wall 56 and the end of the plunger portion 38, as indicated in Figure 8.

By way of still further modification, as illustrated in Figure 8, it is desirable to provide undercuts such as the crosswise extending grooves 62 and 64 in the top wall of the casting over which the disc members 18, 12 and 14 are slideable. Additional grooves in between may be provided with a sufficient number of ribs standing to support the disc members level within the guide slot for lateral displacement. These undercuts reduce the amount of surface in contacting relation with the disc members thereby to minimize the frictional forces existing in operation. In addition, any dirt or other foreign material which finds its way into the selector device can be displaced into the undercuts without interfering with the operation of the device or the free movement of the parts thereby to minimize the necessity for replacement and repair or the frequency of shut-downs for cleaning purposes.

With the undercuts and with the described dimensional relation between the parts, it is possible to make use of the device while located in a vertical or endwise position as well as in the illustrated horizontal position since means are provided for the removal of foreign matter from the operating surfaces and the possibility of free movement of the disc members both rotationally as well as linearly permits displacement freely in any direction independently of position in the machine. Thus the elements can be operated with a minimum amount of friction and wear and without interference and without limitation as to position to permit full flexibility in use.

In operation, the elements may be arranged as illustrated in Figure 1 of the drawing with all of the plungers in their normal forward position of adjustment and with the disc members arranged in side by side relation within the guide slot 16 between the stops 22 and 24 whereby sufficient play exists between the elements to permit a plunger to be projected therebetween but insufficient to permit projection of more than one plunger therebetween. Thus, in selection of an article to be vended, when the proper plunger, such as the plunger 26^a, is displaced manually from normal to operated position of adjustment, the edge portion 66 of the plunger which is located in advance of the disc members is displaced in the direction to engage the lateral curvilinear edge or edges of the disc members in its path whereby the disc members are cammed in the sidewise direction by an amount to permit the plunger to be continued to be displaced rearwardly to position a portion therebetween, as illustrated by the plunger 26^a in Figure 3. The plunger is stopped in operated position of adjustment upon engagement of the stop pin 52 with the front wall 32 of the casting or upon abutment of the rearward end portion of the plunger 26^a with the wall 56 of the machine.

As the plunger is displaced rearwardly, the roller 48 riding on the upper edge of the rearward end portion of the plunger is caused to ride up on the cam edge 40 to rock the switch arm 42 in the counter-clockwise direction about its pivot to make the corresponding switch 44. The switch that is made determines the article to be delivered when the machine is subsequently cycled for carrying out the vending operation. Until the vending cycle is carried out, the vendee is free to change his mind by releasing the plunger for automatic return to normal

position thereby to free the device for operation of a different plunger to effect a desired selection.

When in operated position, the displaced plunger takes up an amount of space between the disc members to prevent displacement of any other plunger. This will be evident from the fact that the free spaced relation between the stops 22 and 24 is adapted to be slightly greater than the thickness of the plunger but less than twice the thickness thereof so that when one plunger is in operated position, the disc members are incapable of being further cammed in the direction away from each other by an amount to enable another plunger to extend therebetween with the result that the disc members tend to block movement of such other plungers from normal to operated positions of adjustment.

When the operated plunger is released, the spring operates automatically to return the plunger from displaced to normal position. The roller 48 on the end of corresponding switch arm 42 rides down the cam surface 40 as it is displaced thereunder for rocking movement of the switch arm to break the switch. As the plunger is returned toward normal position, the portion thereof disposed between the disc members is also withdrawn so that the disc members once more have sufficient play in the sidewise direction to enable the same plunger or any other plunger to be manually displaced from normal to operated positions to make a subsequent selection. It will be apparent that the rolling contact between the disc members with the side walls of the guide slot and with each other permits for free movement responsive to camming action by the plungers and that the alignment of the disc members, at all times, with a curvilinear lateral edge portion in the path of the plungers, notwithstanding the previous displacements thereof, enables the described camming action to be effected for selection so that it becomes possible to effect selection between operations of the machine without the necessity for readjustment of the disc members or return of the disc members to any particular starting position. This provides for complete flexibility in operation and selection without influence on previous settings or operations.

While it is preferred to make use of plungers constructed in the manner described to place a portion thereof between the disc members, when in operated position, it will be understood that other means may be employed responsive to movement of the plunger from normal to operated position to effect the desired displacement and for maintaining the desired spaced relation between the displaced disc members. For example, use may be made of a rocker arm operatively connected to each plunger in a manner to cause rocking movement of the arm into camming engagement with edge portions of the disc members to effect displacement thereof responsive to movement of the plunger from normal to operated positions of adjustment thereby to take up an amount of space between the disc members which blocks movement of other rocker arms for camming action to effect corresponding displacement of the disc members which would otherwise enable the second plunger to be displaced into operated position. Under such circumstances, the amount of lateral movement of the disc members available between the stops will be calculated to be greater than the thickness of the element adapted to be displaced therebetween but less than twice the thickness so that only one such element can be present at any one time and retraction thereof will be necessary responsive to withdrawal of the plunger before another can be operated for selection. Under such circumstances, the plungers would be constructed without having portions adapted to be projected between the disc members.

It will be apparent from the foregoing description that I have provided a simple device of small dimension to control selections of articles to be dispensed from a vending machine and that such unit may be mounted in any position and/or in any location within the machine with-

out interference with the operation thereof. The free movement of the disc members and their alignment with the plungers to enable camming action for displacement, notwithstanding any previous operation of the elements, provides for complete flexibility in selection and operation, yet complete control is available to prevent delivery of other than the one article selected.

It will be understood that a selector device of the type described may also be used to advantage in the selection of one of a plurality of optional operations available in a machine or device or a railroad switching system where it is essential to limit operation to but one of the plurality of optional operations at any one time.

It will be understood that changes may be made in the details of construction, arrangement and operation without departing from the spirit of the invention, especially as defined in the following claims.

I claim:

1. A selector device of the type described comprising a plurality of flat disc members, a housing having a confined disc slot dimensioned to have a length corresponding to the diameter of the disc members, a thickness corresponding to the thickness of the disc members and an effective width greater than the combined diameters of the disc members plus the thickness of the plunger but less than twice the thickness thereof, said disc members being positioned within the disc slot in side by side relation for relative movement in the crosswise direction between the effective width, a plurality of plungers mounted for endwise movement in the housing in a direction lengthwise of the disc slot with recesses of said plunger extending upwardly, said recesses dimensioned to have a length corresponding to the cord of the disc members spaced from the edge by an amount corresponding to the thickness of the plunger and located centrally in the disc slot when in operated position in lengthwise alignment with the lateral edge portions of the disc members, switch means for each plunger, an operative connection between each plunger and the respective switch means for making the switch when the plunger is in operated position, and means constantly urging each of said plungers independently in the direction to align the slotted portion with the crosswise diameters of the disc members.

2. A selector device of the type described comprising a plurality of flat disc members, a housing having a confined slot dimensioned to have a length corresponding to the diameter of the disc members, a thickness corresponding to the thickness of the disc members and an effective width greater than the combined diameters of the disc members plus the thickness of a plunger but less than twice the thickness thereof, said disc members being positioned within the slot in side by side relation to permit relative movement in the crosswise directions between the effective width of the slot, a plurality of plungers mounted for endwise movement in the housing in a laterally spaced apart relation corresponding to the diameter of the disc members, said plungers having portions shiftable in a direction lengthwise through the slot during movement of the plunger between normal and operated positions of adjustment, said portions of the plunger within the slot having recesses dimensioned to have a length corresponding to the cord of the disc members spaced between each by an amount corresponding to the thickness of the plunger and in which the recess is located centrally in the slot when in operated position, switch means for each plunger, an operative connection between each plunger and the respective switch means for making the switch when the plunger is in operated position, and means constantly urging each of said plungers independently in the direction towards normal position.

3. A selector device as claimed in claim 2 in which the recess portion of the plunger within the slot has a depth sufficient to bring the bottom edge thereof flush with the base of the slot over which the coins move.

4. A selector device as claimed in claim 2 in which the base of the slot is formed with a plurality of crosswise extending recesses to minimize the surface area in contact with the disc members during movement.

5. A selector device as claimed in claim 2 in which the plungers are formed with a cam in the upper edge portion outside of the slot and in which the operative connection between a switch and the plunger comprises switch arm means resiliently engaging the edge of the plunger for engagement by the cam during movement between normal and operated positions.

6. A selector device as claimed in claim 2 which includes stop means for limiting movement of the plungers between normal and operated position.

7. A selector device comprising a plurality of plungers, a plurality of flat disc members, a housing having a confined slot dimensioned to have a length corresponding to the diameters of the disc members, a thickness corresponding to the thickness of the disc members and an effective width greater than the combined diameters of the disc members plus the thickness of the plunger adapted to be projected therebetween but less than twice the thickness thereof, said disc members being positioned within the slot in side-by-side relation, said plungers being formed with an upstanding portion within the slot in advance of the disc members and spaced forwardly from the center of the slot by an amount corresponding to the length of stroke of the plungers during movement between normal and operated positions thereby to space

20 the upstanding portion out of contact with the disc members when in normal position and alongside the disc members to occupy space therebetween when in operated position, means mounting the plungers in the housing in laterally spaced-apart relation corresponding to the diameters of the disc members with the upstanding portion of the plungers aligned endwise with the lateral edge portions of the disc members for endwise movement into camming engagement to position the upstanding portion of the plunger alongside the discs to occupy a space

25 therebetween responsive to movement of the plungers from normal to operated positions of adjustment, stop means for each plunger in position to be engaged by the plunger when in operated position of adjustment, and means constantly urging each of said plungers away from

30 the upstanding portion out of contact with the disc members when in normal position and alongside the disc members to occupy space therebetween when in operated position, means mounting the plungers in the housing in laterally spaced-apart relation corresponding to the diameters of the disc members with the upstanding portion of the plungers aligned endwise with the lateral edge portions of the disc members for endwise movement into camming engagement to position the upstanding portion of the plunger alongside the discs to occupy a space

35 therebetween responsive to movement of the plungers from normal to operated positions of adjustment, stop means for each plunger in position to be engaged by the plunger when in operated position of adjustment, and means constantly urging each of said plungers away from

40 the upstanding portion out of contact with the disc members when in normal position and alongside the disc members to occupy space therebetween when in operated position, means mounting the plungers in the housing in laterally spaced-apart relation corresponding to the diameters of the disc members with the upstanding portion of the plungers aligned endwise with the lateral edge portions of the disc members for endwise movement into camming engagement to position the upstanding portion of the plunger alongside the discs to occupy a space

45 therebetween responsive to movement of the plungers from normal to operated positions of adjustment, stop means for each plunger in position to be engaged by the plunger when in operated position of adjustment, and means constantly urging each of said plungers away from

50 the upstanding portion out of contact with the disc members when in normal position and alongside the disc members to occupy space therebetween when in operated position, means mounting the plungers in the housing in laterally spaced-apart relation corresponding to the diameters of the disc members with the upstanding portion of the plungers aligned endwise with the lateral edge portions of the disc members for endwise movement into camming engagement to position the upstanding portion of the plunger alongside the discs to occupy a space

55 therebetween responsive to movement of the plungers from normal to operated positions of adjustment, stop means for each plunger in position to be engaged by the plunger when in operated position of adjustment, and means constantly urging each of said plungers away from

60 the upstanding portion out of contact with the disc members when in normal position and alongside the disc members to occupy space therebetween when in operated position, means mounting the plungers in the housing in laterally spaced-apart relation corresponding to the diameters of the disc members with the upstanding portion of the plungers aligned endwise with the lateral edge portions of the disc members for endwise movement into camming engagement to position the upstanding portion of the plunger alongside the discs to occupy a space

65 therebetween responsive to movement of the plungers from normal to operated positions of adjustment, stop means for each plunger in position to be engaged by the plunger when in operated position of adjustment, and means constantly urging each of said plungers away from

70 the upstanding portion out of contact with the disc members when in normal position and alongside the disc members to occupy space therebetween when in operated position, means mounting the plungers in the housing in laterally spaced-apart relation corresponding to the diameters of the disc members with the upstanding portion of the plungers aligned endwise with the lateral edge portions of the disc members for endwise movement into camming engagement to position the upstanding portion of the plunger alongside the discs to occupy a space

75 therebetween responsive to movement of the plungers from normal to operated positions of adjustment, stop means for each plunger in position to be engaged by the plunger when in operated position of adjustment, and means constantly urging each of said plungers away from

76 the upstanding portion out of contact with the disc members when in normal position and alongside the disc members to occupy space therebetween when in operated position, means mounting the plungers in the housing in laterally spaced-apart relation corresponding to the diameters of the disc members with the upstanding portion of the plungers aligned endwise with the lateral edge portions of the disc members for endwise movement into camming engagement to position the upstanding portion of the plunger alongside the discs to occupy a space

thickness of the plunger and located centrally in the disc slot when in operated position in lengthwise alignment with the lateral edge portions of the disc members, switch means for each plunger, and an operative connection between each plunger and the respective switch means for making the switch when the plunger is in operated position.

12. A selector device of the type described comprising a plurality of flat disc members, a housing having a confined slot dimensioned to have a length corresponding to the diameter of the disc members, a thickness corresponding to the thickness of the disc members and an effective width greater than the combined diameters of the disc members plus the thickness of a plunger but less than twice the thickness thereof, said disc members being positioned within the slot in side-by-side relation to permit relative movement in the crosswise directions between the effective width of the slot, a plurality of plungers mounted for endwise movement in the housing in a laterally spaced apart relation corresponding to the diameter of the disc members, said plungers having portions shiftable in a direction lengthwise through the slot during movement of the plunger between normal and operated positions of adjustment, said portions of the plungers within the slot having recesses dimensioned to have a length corresponding to the cord of the disc members spaced between each by an amount corresponding to the thickness of the plunger and in which the recess is located centrally in the slot when in operated position, switch means for each plunger, and an operative connection between each plunger and the respective switch means for making the switch when the plunger is in operated position.

13. A selector device comprising a plurality of the flat disc members, a housing having a confined disc slot dimensioned to have a length corresponding to the diameter of the disc members, a thickness corresponding to the thickness of the disc members and an effective width greater than the combined diameters of the disc members plus the thickness of the plunger but less than twice the thickness thereof, said slot being formed with spaced-apart 40 grooves extending crosswise in the bottom wall portion thereof over which the disc members slide during displacement, said disc members being positioned within the disc slot in side-by-side relation for relative movement in the crosswise direction between the effective width, a plurality of plungers mounted for endwise movement in the housing in a direction lengthwise of the disc slot

5

10

with a recess in the upper edge of the plunger dimensioned to have a length corresponding to the cord of the disc members spaced from the edge thereof by an amount corresponding to the thickness of the plunger and located centrally in the disc slot when in operated position in lengthwise alignment with the lateral edge portions of the disc members, switch means for each plunger, and an operative connection between each plunger and the respective switch means for making the switch when the plunger is displaced to operated position.

14. A selector device comprising a plurality of plungers, a plurality of flat disc members, a housing having a confined slot dimensioned to have a length corresponding to the diameter of the disc members, a thickness corresponding to the thickness of the disc members and an effective width greater than the combined diameter of the disc members plus the thickness of a portion of the plunger adapted to be projected therebetween but less than twice the thickness thereof, said disc members being positioned 15 within the slot in side-by-side relation, means mounting the plungers in the housing in laterally spaced-apart relation corresponding to the diameters of the disc members and aligning said plungers with the lateral edge portions of the disc members for endwise movement into camming engagement to position a portion of the plunger alongside the discs to occupy a space corresponding to the difference between the combined diameters of the disc members and the effective length of the slot responsive to movement of the plungers from normal to operated 20 positions of adjustment, means for each plunger in position to be engaged by the plunger when in operated position of adjustment, switch means for each plunger, a cam on the upper edge of each plunger, and a switch arm on the switch means which rides upon the upper edge of the plunger in advance of the cam for making the switch as the switch arm is displaced by the cam responsive to movement of the plunger from normal to operated position.
